THREAD CUTTING SHUTTLE

Albert Cederlund, Worcester, Mass., assignor to
 Crompton & Knowles Loom Works, Worcester,
 Mass., a Corporation of Massachusetts

Application February 20, 1931. Serial No. 517,263

9 Claims. (Cl. 139—196)

This invention relates to shuttles constructed to cut the thread of the outgoing bobbin at the time of transfer and it is the general object of the invention to provide such a shuttle having 5 the cutting edges so arranged as to insure a drawing of the weft across sharp edges due to the outgoing movement of the bobbin.

In weft replenishing looms wherein the bobbins are changed it is customary to expel the 10 exhausted bobbin by means of incoming full supply of weft. Where feeler mechanisms are employed there is usually a thread end extending from an exhausted bobbin through the shuttle eye, back along the front wall of the shuttle eye, back along the front wall of the shuttle 15 to the adjacent selvage. It is necessary to withdraw this end and a part of the mechanism for accomplishing this result usually involves some form of thread parter. It is an important object of my present invention to effect the thread 20 parting by means located in the shuttle and so disposed with respect to the thread passage as to be normally out of the path of the weft as the latter unwinds in weaving, but positioned to lie in the path of the weft as the latter is 25 depressed at the time the exhausted bobbin is pushed downwardly and out of the shuttle.

It is a further object of my invention to provide two cutting edges so related to each other 30 that a thread when being drawn downwardly at the time of transfer will be caused to move over two surfaces at least one of which is sharp.

It is a still further object of my invention to provide the passage in the shuttle eye with an auxiliary restricted chamber the sides of which 35 act as guards to keep the thread from engaging the cutting edges under normal conditions, said auxiliary passage being of sufficient width only to require the thread to slide over the cutting edges and being of just sufficient width to accommodate the thread. This passage may have 40 an inclined bottom which extends upwardly from the bottom of the shuttle toward the adjacent shuttle tip without materially weakening the cross section of the shuttle.

45 At the instant of transfer there may develop a slight amount of slack which permits the movement of the weft away from the cutting edge carried by the shuttle. It is a further object of my invention to employ a slack to take-up shuttle eyes which will serve to hold the weft taut by taking up the slack, thus requiring the thread to be drawn over the sharp edges.

50 With these and other objects in view which will appear as the description proceeds, my invention resides in the combination and ar-

rangement of parts hereinafter described and set forth in the claims.

In the accompanying drawing, wherein a convenient embodiment of my invention is set forth,

Fig. 1 is a top plan view of one end of shuttle 60 made according to my present invention,

Fig. 2 is an enlarged vertical section on line 2—2 of Fig. 1,

Fig. 3 is an enlarged vertical section on line 3—3 of Fig. 1,

Fig. 4 is a detail of one of the cutter plates, and

Fig. 5 is a diagrammatic fragmentary view showing the relation between the weft and the cutter at the time of transfer.

70 Referring to the drawing, the shuttle S has a weft chamber 10 in which is located the ordinary bobbin B having a weft supply W. Extending from the chamber 10 is the usual thread passage 11 which as set forth herein may have 75 a form of tension such as that shown in patent to Hutchins No. 1,723,423. The operation of my invention does not depend primarily upon any particular form of shuttle tension, but the thread, after passing through the tension, may 80 issue from a delivery eye 12 of usual form. The floor of the thread passage is designated at 13 and will ordinarily be a substantial distance above the bottom of the shuttle.

85 In applying my invention to the form of shuttle set forth herein I employ a pair of substantially similar cutting plates designated herein at 20 and 21, being located on the right and left hand sides, respectively, of the passage as shown in Fig. 2. As shown in Fig. 4 each plate 90 comprises a sheet of tempered steel the upper edge 22 of which may be inclined downwardly and toward the center of the shuttle and preferably blunt so as to have no cutting action on the thread. The left hand ends of the particular plate shown in Fig. 4 has a sinuous sharpened edge 23 formed with upper and lower protuberances 24 and 25, respectively, between which lies a recess 26.

100 Both of the cutters are substantially the same and can be mounted as suggested in Fig. 1, being held in place by screws or other means. A spacer 27 may be employed in connection with one of the plates to hold the same a short distance from the other plate. When assembled as 105 shown in Fig. 2 the protuberances 24 of each plate will lie in approximately the same horizontal plane and this is also true of the lower parts 25. The recesses 26 may be disposed as shown in Fig. 2, but it is desirable that they 110

overlap slightly so that at no time in the downward movement of the thread will the latter be free from a bending condition induced by engagement with the cutting edges.

- 5 A small slot or recess 30 extends vertically downwardly from the bottom 13 and has an inclined floor 31 which, as shown in Fig. 3, may start near the lower protuberance 25 and slant upwardly and toward the adjacent shuttle tip.
- 10 The recess 30 is preferably of a width equal to or only slightly more than the amount by which the protuberances overlap each other, as illustrated in Fig. 2. This relation is not absolutely necessary but is convenient. That part of the
- 15 floor 13 which is adjacent the blunt edges 22 may be located slightly above the latter so that should any burr or sharp edge happen to remain along the edges 22 said floor of the passage 11 will be sufficiently high to act as a guard and prevent the thread from engaging the burr or the like. If care is taken to round that part of edge 22 which faces the weft chamber 10 the guarding relation mentioned will not be necessary.

20 In operation, when the bobbin has a sufficient supply of weft, it will extend in a direction parallel to the axis of the shuttle and will unwind over the tip of the bobbin B and enter the thread passage 11. Weft ordinarily balloons somewhat when unwinding rapidly and moves along a curved path which merges with the side walls of the passage 11. As the weft is on the under side of its path of movement when being unwound from the bottom of the bobbin, it will slide along the previously referred to guarding portions of the floor 11, or may slide over properly smoothed or rounded edges 22. In any event, the parts will be so proportioned that the previously described cutting edges will normally be out of the path of movement of the weft as the shuttle is in flight.

25 At the time of transfer well-known mechanism will operate to depress the bobbin so that the same will move from the full to the dotted line position indicated in Fig. 3. The weft will be guided down one or the other of the oppositely inclined edges 22 and will enter the small recess 30. As the bobbin continues to move downwardly the weft will be dragged over the cutting edges of both plates 20 and 21. The contours of these cutting edges are such as to require the thread to be bent as shown in Fig. 5.

30 An important feature of the invention relates to the draw-back tension in the shuttle eye. The Hutchins shuttle previously referred to includes two tension arms 40 and 41, respectively, held normally apart by an elastic, such as a rubber band 42. The inclined parts of the arms defined a notch into which the weft of the freshly transferred bobbin is directed. During shuttle flight the arms are believed to be stressed and to remain so as the shuttle comes to rest. The elastic is therefore capable of 35 moving the arms to take up any slack which might occur at transfer and hold the weft taut as it passes over the cutting edges.

35 From the foregoing it will be seen that downward movement of the bobbin insures a sliding contact of the weft along a zigzag or sinuous path defined by two sharp edges with the result that the weft is cut by the movement which is given it at the time the bobbin is transferred. Also, the cutting edges are guarded and the

40 small vertical recess with the inclined bottom

aids the weft to move to cutting position. Furthermore, the draw-back tension helps to maintain the weft taut as it moves over the knives.

Having thus described my invention it will be seen that changes and modifications may be made therein by those skilled in the art without departing from the spirit and scope of the invention and I do not wish to be limited to the details herein disclosed, but what I claim is:

1. In a thread cutting shuttle having a bobbin chamber and an eye thread passage, a pair of stationary overlapping oppositely facing cutting edges between the passage and chamber and located below the center of the shuttle to engage and sever the weft of an outgoing bobbin. 85

2. In a thread cutting shuttle having a bobbin chamber and an eye thread passage, a pair of oppositely facing cutting surfaces spaced longitudinally with respect to the shuttle and overlapping transversely of the shuttle, said cutting edges located in the path of a weft extending from an outgoing bobbin. 95

3. In a thread cutting shuttle having a bobbin chamber and an eye thread passage, a pair of longitudinally spaced cutters each having a 100 sinuous cutting edge, said cutting edges overlapping each other in a direction transversely of the shuttle, the edges being so disposed as to produce a bend in a weft extending from the thread passage to a bobbin leaving the bobbin 105 chamber.

4. In a thread cutting shuttle having a bobbin chamber and an eye thread passage, the thread passage having a floor located in the bottom of the shuttle, and a pair of longitudinally spaced cutting edges both located between the floor of the thread passage and the bottom of the shuttle and having portions which overlap transversely of the shuttle and positioned to engage a weft extending from a thread passage to 115 an outgoing bobbin.

5. In a thread cutting shuttle having a bobbin chamber and an eye thread passage, the thread passage having a floor located in the bottom of the shuttle, and a pair of longitudinally spaced cutting edges both located between the floor of the thread passage and the bottom of the shuttle and having portions which overlap transversely of the shuttle and positioned to engage a weft extending from a thread passage to 125 an outgoing bobbin, the floor of the thread passage having a restricted recess which is in substantial longitudinal alignment with the cutting edges.

6. In a thread cutting shuttle having a bobbin chamber and an eye thread passage, the thread passage having a floor located in the bottom of the shuttle, and a pair of longitudinally spaced cutting edges both located between the floor of the thread passage and the bottom of the shuttle and having portions which overlap transversely of the shuttle and positioned to engage a weft extending from the thread passage to an outgoing bobbin, the floor of the thread passage having a restricted recess which is in 130 substantial longitudinal alignment with the cutting edges and terminates at a point above said cutting edges.

7. In a thread cutting shuttle having a bobbin chamber and an eye thread passage, the thread passage having a floor located in the bottom of the shuttle, and a pair of longitudinally spaced cutting edges both located between the floor of the thread passage and the bottom of the shuttle and having portions which overlap 135

140

transversely of the shuttle and positioned to engage the weft extending from the thread passage to an outgoing bobbin, the floor of the thread passage having a restricted recess which is in substantial longitudinal alignment with the cutting edges and extends from a point adjacent the bottom of said cutting edges to a point above the latter.

8. In a thread cutting shuttle having a weft chamber to hold a bobbin, a draw-back tension for the weft, and a stationary cutter on the shuttle located between the chamber and tension, and operative at the transfer of a bobbin

to cut the filling extending from said bobbin as the latter moves from the weft chamber.

9. In a thread cutting shuttle having a bobbin chamber and an eye thread passage, a pair of oppositely facing stationary members between the passage and chamber and located below the center of the shuttle, one of the members having a cutting edge, and the other member overlapping the cutting edge with respect to the path of the weft to produce a cutting action on the outgoing weft by movement of the latter.
